Assignors to

North, Chase, & North of Philadelphia, Pa.
Letters Patent No. 601. Dated Oct. 4th, 1853.

The schedule referred to in these Letters Patent, and making part of the same.

To all whom it may concern:

Be it known, that we, Garrettson Smith and Henry Brown of the County of Philadelphia, and State of Pennsylvania, have invented a new and improved design for stoves, of which the following is a full and exact description, reference being had to the accompanying drawings making part of this specification, in which

Fig. 1 represents a front plate & door,

Fig. 2, " " back plate,

Fig. 3, " " side plate,

Fig. 4, " " top plate,

Fig. 5, " " foot.

a, b, c are mouldings.

The ornamental work is composed of vines, flowers, scrolls, and mouldings, as represented in the drawings.

What we claim as our invention and desire to secure by Letters Patent is the design and configuration of the mouldings and ornamental work, as herein described, forming an ornamental design for a stove.
